BUILDING COVERING

Edward R. Black, Chicago, Ill., assignor to
 Edward R. Black, James E. Black, and Elam L.
 Black, doing business as Black Systems, Chi-
 cago, Ill., a copartnership

Application January 9, 1941, Serial No. 373,764

9 Claims. (Cl. 108—7)

My invention relates to building coverings.

More particularly it relates to shingles of the interlocking type made from flexible prepared roofing material of the usual varieties and intended for covering the roofs and side walls of buildings.

One of the objects of the invention is to provide improved interlocking shingles which may be laid to afford a hexagonal pattern on the roof or side wall—a pattern which has wide popularity.

Another object is to provide shingles which, when so laid, will expose uninterrupted or continuous lateral or side edges and thereby enhance the appearance of the design.

A further object is to provide an interlocking type shingle which lends itself to easy laying because it is unnecessary to raise the bodies of shingles in order to interlock those of adjacent courses and because the correct relative positions of adjacent shingles in the same course is insured by merely bringing portions together in abutting relation.

Another object is to provide shingles which, when interlocked, will lay with their exposed edges flat and tightly down against the underlying shingles.

Another object is to provide shingles in which interlock is effected by a wedging movement between adjacent underlying shingles and the overlapping shingle—a wedging action which facilitates proper positioning of the butt edge of the overlying shingle with respect to the underlying shingles to insure the intended overlap.

Another object is to provide shingles which may be economically laid in that a satisfactory overlap can be obtained with a minimum of material.

Another object is to provide a shingle and cutting layout which will conserve material and such that all edges that will be exposed and those used for gaging position are cut edges, whereas the only shingle edge formed by an edge of the stock sheet is an edge which will be covered when shingles are laid.

Other objects and advantages will hereinafter appear.

In the drawings:

Fig. 1 is a plan of a shingle of a form that will produce the more commonly proportioned hexagonal pattern;

Fig. 2 is a plan of a part of a roof covering showing how the shingles are laid and the pattern produced thereby;

Fig. 3 is an enlarged section on the line 3—3 of Fig. 2;

Fig. 4 is an enlarged section on the line 4—4 of Fig. 2; and

Fig. 5 is a plan of a strip of sheet stock showing how shingles can be cut therefrom to best advantage.

In general my improved shingle comprises a body of flexible prepared roofing material having a margin composed principally or in the main of a butt edge and a tip edge of substantially equal length, of a pair of lower lateral side edges which converge at substantially equal angles from the butt edge and of a pair of upper lateral side edges that converge at substantially equal angles from the tip edge. The body at or near the butt edge is provided with two converging slits which open at the margin and run inwardly substantially parallel to the lower lateral side edges so as to create a tapered tongue of which the free and larger end is the butt edge. There is also provided a pair of triangular shaped tabs which project from the body at the upper ends of the lower lateral side edges.

Theoretically the proper location for the slits to open into the margin of the body is at the angles where the butt edge joins the two lateral side edges, but because the roofing material has substantial thickness—usually about $\frac{1}{8}$ inch—this theoretical relation is not in practice the best. To give proper results these slits should open either in the butt edge or in the two lower lateral side edges—and in either event at a distance of about the thickness of the material from the point where the lower lateral side edges meet the butt edge. My preference is to have them open into the lower lateral side edges and that arrangement will be shown and described.

Referring first to Fig. 1, the covering unit or shingle, which is cut from a strip of flexible prepared roofing material of any of the approved varieties, has a generally hexagonal appearance with a butt or exposure edge 5 and a tip or normally concealed edge 6. The butt and tip edges are of equal length. Converging at equal angles from the two ends of the butt edge are two lower lateral side edges 7 and 8. Converging at equal angles from the ends of the tip edge are two upper lateral side edges 9 and 10. The two lateral side edges 7 and 9, which form the major part of one side of the shingle, do not meet but have interposed therebetween a series of angularly related marginal lines 11, 12, 13, 14 and 15 which define a laterally projecting wing 16. The lines 14 and 15 define a triangular shaped tab 17 which serves,

as will be later explained, to lock down one end of the butt edge of an overlying shingle. The marginal lines 11 and 12 define a right angled projection which serves as a location indicator as will presently appear. In a somewhat similar manner the lateral side edges 8 and 10 do not extend straight to a point of juncture but have interposed therebetween the angularly related marginal lines 25, 26, 27 and 28—the lines 27 and 28 defining a triangular shaped tab 29 which is symmetrically placed relative to tab 17 and serves to lock down the opposite end of the butt edge of the overlying shingle. The right angled projection formed by the lines 25 and 26 serves as a positioning gage as will be later explained. The butt of the shingle is provided with two converging cuts or slits 35 and 36 which, at their inner ends, terminate in short outwardly directed cuts 37 and 38, respectively. These slits 35 and 36 extend into the butt from a point removed from the respective end of the butt edge a distance substantially the thickness of the stock material and at such angles as will align with the upper marginal edges of the two underlying shingles of the immediately preceding horizontal course when in location on the roof or side wall. The length of the terminal cuts 37 and 38 is preferably equal to or slightly in excess of the thickness of the material; they facilitate the proper placement of the shingles and serve to prevent the tearing of the material at the ends of the slits when, as will later appear, the tongue and body are relatively displaced to provide gaps for the locking tabs 17 and 29 of underlying shingles. The cuts 35—37 and 36—38 form a tongue 40 which is partly overlaid by the tabs 17 and 29 of two shingles of the immediately preceding course. Preferably a short triangular shaped gaging tab 41 projects from the tip edge 6 in such location that its straight side 42 is on the vertical median line of the shingle.

To give the best results, slits 35 and 36 extend from the edges into the shingle body at an angle such that each is substantially parallel to the opposite lower lateral side edge. That is, slit 35 is substantially parallel to side 8, and slit 36 is substantially parallel to side 7. Also the best length of these slits in relation to the length of the sides of tabs 17 and 29 is such that the length of side 15 of tab 17 and of side 28 of tab 29 is substantially equal to the projection of a slit upon the butt edge 5; and such that the length of side 14 of tab 17 and of side 27 of tab 28 is substantially equal to the projection of a slit upon a line perpendicular to butt edge 5. When so proportioned the tongue 40, which has the butt edge 5 as its free end boundary, includes two triangular portions of substantially the size and shape of the tabs 17 and 29. And when the shingles are laid, as will be now explained, only the tabs on opposite sides of two adjacent shingles in the same course overlie the intervening (i. e., staggered) shingle of the next succeeding overlapping course.

Referring more particularly to Fig. 2, the method of laying, gaging and interlocking and the advantages secured will be explained. In general, the shingles are laid in the customary relation of vertically and horizontally overlapping courses, shingles in adjacent horizontal courses being staggered. Thus, Fig. 2 shows the relation in five horizontal courses A, B, C, D and E, the laying progressing from eave to ridge and from left to right.

First the shingles of course A are laid with the

butt edges 5 in horizontal alignment. Of course, it will be understood that at the eave there will be a preceding course of shingles cut across in line with the lower edges 15 and 28 of the locking tabs 17 and 29 and staggered with relation to these course A shingles, or, if desired, a starting strip may be used to underlie the shingles of the A course and cover the roof-eave edges therebetween. The shingles are laid so that the edge portion 25 at the left hand side of one shingle abuts the edge portion 12 at the right hand side of the shingle immediately at its left and with the horizontal edge portions 13 and 26 in alignment, as clearly shown at the right end of Fig. 2. Thus the edge portions 12 and 25 serve to gage horizontally and the edge portions 13 and 26 serve to gage vertically the correct relative positions of shingles in the same course. That is, the positions are correct when these portions of adjacent shingles in the same course touch each other and align—a condition easy to detect. The first course shingles may be anchored down to the building framework by nails 45 and 46 driven through the units at about the horizontal median line and near the outer lateral edges as shown in Fig. 2.

After the A course is completely or partly in place, the laying of the B course may commence. The correct position of the first shingle B' of this second course is determinable in several ways. First, it is drawn up into the crotch formed by the converging lower lateral side edges 7 and 8 of the two shingles A' and A'' in the immediately preceding or A course with which it is staggered. During this drawing up process the triangular edge tab 17 of shingle A' and the triangular tab 29 of shingle A'' are slightly raised—either by elevating them or the shingle edges—so that the outer corners 50 and 51 of the tongue 40 of shingle B' can be slid under the tabs 17 and 29 of shingles A' and A''. The interfitting of the tongue beneath tabs 17 and 29 is facilitated by bending the tongue inwardly toward the roof. Shingle B' is thus drawn up into wedging relation to shingles A'—A'' of the immediately preceding course until its butt edge 5 aligns with the edge portions 15 and 28 of the triangular tabs 17 and 29 of the shingles A'—A'' of the preceding course. When this condition obtains the lower edge 5 of tongue 40 formed by slits 35 and 36 of shingle B' aligns with the converging edges 7 and 8 of the shingles A'—A'' and the edge portion 25 of shingle B' should align with the edge 42 of gaging tab 41 of shingle A'. Also the edge portion 12 of shingle B' will align with the edge 42 of gaging tab 41 of shingle A''. When thus positioned the shingle B' is anchored down to the building framework by nails 45 and 46 driven therethrough in the same relative location as for the shingles of the A course.

The laying of the rest of the shingles in the B course proceeds from left to right by a repetition of the procedure explained in connection with shingle B'.

After the laying of all or a part of the B course, the laying of the C course shingles C'—C'', etc., may commence—their relation to the shingles in the B course being the same as that previously explained with respect to the relation of shingles in the B course to those in the A course. Then comes the D course, followed by the E course, and so on in repetition until the whole roof or side wall is covered. Of course, it will be understood that the laying can proceed in the opposite direction—i. e., from right to left—if desired.

The relation existing at the butts of shingles in one course and the converging lower lateral edges of the two interlocking adjacent shingles in the immediately preceding course will be best understood by referring to Figs. 3 and 4. As here clearly shown, the tongue 40 is held down by the overlying triangular projecting tabs 17 and 29 of the staggered shingles in the next preceding course, which shingles are anchored to the building framework by nails in that immediate vicinity. The interlock is not between a butt region of an overlying shingle and straight edges of the two underlying shingles but between the closed ends of the slits 35 and 36 and the crotches formed by the edges 13-14 and 26-27 of the underlying shingles. This feature facilitates the proper locating of the overlying shingles with respect to the interlocking underlying shingles because there is only one relationship when the overlying shingle is completely pulled up into the crotch between the underlying shingles and that is the proper one. The two converging edges of tongue 40 formed by the slits 35 and 36 lie in line with the lower lateral side edges 8 and 7, respectively, of the immediately underlying shingles so that no part of the tongue 40, for example of the shingle C'', lies under any part of the body of the underlying shingles of the next preceding course, for example shingles B' and B'', but only under the projecting triangular shaped tabs 29 and 17 thereof. Thus the tabs 17 and 29 of underlying shingles hold down the tongues 40—and consequently the butt edges 5—of overlying shingles; and the inherent flexibility of the material results in the tabs being able to curve upwardly through the gaps provided by the relative displacement of a tongue and the shingle body on opposite sides of the slits 35 and 36, and, after projecting through those gaps, to lie flat against the upper surface of the tongue. This flexibility also insures that the tongue 40 will bend abruptly over the edges 13 and 26 of the underlying shingles to take up about the thickness of the material in the length of the tongue so that the corners formed by edge 8 and slit 36 and by edge 7 and slit 35 will lie immediately over the corners in the underlying shingles formed by the edges 8-28 and 7-15, respectively. This relationship provides a butt edge exposure of substantially the length of the butt edge 5 so as to maintain the hexagonal pattern when the shingles have been finally laid. The projecting tabs 17 and 29 of underlying shingles hold down the tongue 40—and consequently the butt—of an overlying shingle and the weight of the overlying shingle helps to keep down the tabs of the underlying shingles.

It will be observed that the overlying shingles overlap the underlying shingles, both vertically and horizontally, adequately to insure against leakage. For a typical example, assume a shingle wherein the lower lateral side edges converge from the butt edge by angles of 135 degrees and the upper lateral side edges converge from the tip edge by the same angles and the units measure 16 inches between edges 7-10 and 16 inches between edges 8-9. With shingles of this shape and size and those in the same course overlapped 2½ inches measured perpendicularly to the overlapping edge, there is afforded an effective lateral or horizontal overlap of approximately 3½ inches and a square of roof can be properly covered by approximately 146 square feet of material.

Fig. 5 shows how the shingles may be effectively cut with little waste from strips of roofing

stock of the standard widths and requiring no trimming along either edge of the stock strip. Thus it will be observed that no edge which is exposed when the shingle is laid in the roof covering and likewise no edge which constitutes either a part of the interlock or a positioning gage lies in the stock edges X and Y. The only waste is that shown by the small rectangles Z along the center line of the stock sheet and the small irregular pieces W along the two edges of the stock sheet.

Of course, by changing the angles at which the lower lateral edges converge from the butt edge and at which the upper lateral edges converge from the tip edge, the proportions of the hexagonal pattern may be altered.

Having thus illustrated and explained the nature and one embodiment of my invention, what I claim and desire to secure by United States Letters Patent is as follows:

1. A shingle of flexible prepared roofing material comprising a body the margin of which includes a butt edge and a tip edge of substantially equal length, two lower lateral side edges converging at substantially equal angles from the butt edge and two upper lateral side edges converging at substantially equal angles from the tip edge, the body having a pair of converging slits which open into the margin and form in the body a tongue of which the butt edge constitutes the free end; and a pair of triangular shaped tabs extending outwardly from the body at the tops of the lower lateral side edges.

2. A shingle of flexible prepared roofing material comprising a body having a butt edge and a tip edge of equal length and four additional side edges which in pairs are parallel, the two side edges adjacent the butt edge each having a slit which opens therein at a distance approximately the thickness of the material from the junction of the side and butt edges, and a pair of triangular tabs projecting outwardly from the slitted side edges at equal distances from the ends of the butt edge.

3. A shingle of flexible prepared roofing material comprising a body having a butt edge and a tip edge of equal length and four additional side edges which in pairs are parallel, the two side edges adjacent the butt edge each having a slit which opens therein at a distance approximately the thickness of the material from the junction of the side and butt edges, and a pair of triangular tabs projecting outwardly from the slitted side edges at equal distances from the ends of the butt edge, the lower edges of said tabs being parallel to the butt edge.

4. A shingle of flexible prepared roofing material having a butt edge and a tip edge of equal length, two lower lateral side edges extending at like angles from opposite ends of the butt edge, two upper lateral side edges diverging at like angles from the lower lateral side edges and converging to the top edge, and a triangular tab at the top end of each lower lateral side edge, the shingle having a slit extending at an angle to each lower lateral side edge from a point in that edge removed from its junction with the butt edge by approximately the thickness of the material.

5. A shingle of flexible prepared roofing material having a butt edge and a tip edge of equal length, two lower lateral side edges extending from opposite ends of the butt edge at angles of 135 degrees thereto, two upper lateral side edges diverging from the lower lateral side edges at angles of 90 degrees, and a triangular shaped tab

at the top end of each lower lateral side edge, the shingle having a slit extending at right angles to each lower lateral side edge from a point in that edge removed from its junction with the butt edge by approximately the thickness of the material.

6. A shingle of flexible prepared roofing material comprising a body having a butt edge and a tip edge of equal length and parallel to each other, a pair of lower lateral side edges converging at equal angles from the ends of the butt edge, a pair of upper lateral side edges converging from the ends of the tip edge at angles the same as those at which the lower lateral side edges converge from the butt edge, 10 each of the lower lateral side edges having a slit opening therein and extending into the body substantially parallel to the other lower lateral side edges to form a tongue of which the butt edge is the free end, and a pair of like right angled triangular tabs extending outwardly from the body at the upper ends of the lower lateral side edges, the lower edges of said tabs being parallel to the butt edge and each lower edge of a length substantially equal to the projection of a slit upon the butt edge.

7. A shingle of flexible prepared roofing material comprising a body having a butt edge and a tip edge of equal length and parallel to each other, a pair of lower lateral side edges converging at equal angles from the ends of the butt edge, a pair of upper lateral side edges converging from the ends of the tip edge at angles the same as those at which the lower lateral side edges converge from the butt edge, 20 each of the lower lateral side edges having a slit opening therein and extending into the body substantially parallel to the other lower lateral side edge to form a tongue of which the butt edge is the free end, and a pair of like right angled triangular tabs extending outwardly from the body at the upper ends of the lower lateral side edges, the lower edges of said tabs being parallel to the butt edge and each lower edge of a length substantially equal to the projection of a 25 slit upon the butt edge and the side edges of the tabs each being of a length substantially equal to the projection of a slit upon a line perpendicular to the butt edge.

8. A building covering comprising a plurality of shingles of flexible weatherproof material laid in vertically overlapping horizontal courses; each unit comprising a body having a butt edge and a tip edge of equal length, a pair of lower lateral side edges converging at equal angles from the butt edge and each such edge having a slit opening therein at a distance from an end of the butt edge approximately the thickness of the material and extending into the body of the shingle substantially parallel to the opposite lower lateral side edge, and a pair of triangular tabs projecting from the upper ends of the lower lateral side edges; the shingles in the same course being laid in abutting relation and staggered with respect to the shingles in adjacent courses so that the butt of a shingle in one course lies in the crotch formed by the lower lateral side edges of the two adjacent shingles in the next preceding course and its slits receive triangular tabs from such adjacent shingles in the next preceding course.

9. A building covering comprising a plurality of shingles of flexible weatherproof material laid in vertically overlapping horizontal courses; each unit comprising a body having a butt edge and a tip edge of equal length, a pair of lower lateral side edges converging at equal angles from the butt edge and each such edge having a slit opening therein at a distance from an end of the butt edge approximately the thickness of the material and extending into the body of the shingle substantially parallel to the opposite lower lateral side edge, the slits forming an inwardly tapering tongue of which the butt edge of the shingle is the free end, and a pair of triangular shaped tabs projecting from the upper ends of the lower lateral side edges; the shingles in the same horizontal course being laid in abutting relation and staggered with respect to the shingles in adjacent courses so that the tapering tongue in the butt of the shingle lies in the crotch formed by the lower lateral side edges of the two adjacent overlapped shingles in the next preceding course and is on opposite sides overlaid only by tabs on those overlapped shingles.

EDWARD R. BLACK.
